UNITED STATES PATENT OFFICE.

CHARLES R. HESTER, OF NEW YORK, N. Y.

DESIGN FOR A HAT-DISPLAY STAND.

51,316.

Specification for Design.

Patented Oct. 2, 1917.

Application filed July 25, 1917. Serial No. 182,763. Term of patent 3½ years.

To all whom it may concern:

Be it known that I, CHARLES R. HESTER, a citizen of the United States, residing in the city of New York, borough of Manhattan, in the county and State of New York, have invented a new, original, and ornamental Design for a Hat-Display Stand, of which the following is a specification, reference being had to the accompanying drawing, forming part thereof.

Figure 1 is a perspective view of a hat display stand showing my new design; and Fig. 2 is a plan view.

I claim:

The ornamental design for a hat display stand, as shown.

CHARLES R. HESTER.

Witnesses:

KATHARINE A. HEENAN,
CHARLES E. KOALENZ.
